VENTILATOR OPERATING MECHANISM (FOR GREENHOUSES)

Filed April 18, 1928

Inventor:
Philip L. Mc KEE,
By Cheever & Cox Atty.

UNITED STATES PATENT OFFICE

PHILIP L. MCKEE, OF CHICAGO, ILLINOIS

VENTILATOR OPERATING MECHANISM (FOR GREENHOUSES)

Application filed April 18, 1928. Serial No. 270,892.

My invention relates to operating mechanisms for ventilators and the like, and particularly to means adaptable for use in connection with the operation of ventilator sashes for greenhouses.

In general, one of the primary objects of my invention is to provide an efficiently operable device for controlling the movement of ventilator sashes and devices of like nature, said operating mechanism being of such a nature as to permit the movement or displacement of a ventilator sash within predetermined limits.

More specifically, an object of my present invention is to prevent ventilator sashes and the like which are operated through the agency of chains or other flexible means from being opened beyond a predetermined limit, and to this end I propose to provide a connecting link in association with the flexible actuating means or chain which will limit the longitudinal movement of said chain.

A still further object of my invention is to provide a ventilator actuating device which includes a flexible member or chain which is adapted to be guided over suitable pulleys or sprockets, and to limit the longitudinal movement of said flexible member or chain I propose to connect one extremity of a link member to one of the reaches of said chain, the opposite extremity of the connecting link being suitably secured in a fixed position or secured to the other reach of said chain, the distance through which the chain may be moved, being determined by the length and relative position of said connecting link.

In addition to the above mentioned characteristics, my invention contemplates the provision of a ventilator operating mechanism which lends itself structurally for use in connection with greenhouse ventilator sashes and to this end I provide a flexible actuating chain or cord disposed between a pair of pulleys or sprockets, the upper pulley or sprocket being operatively connected with a rack and pinion device for opening and closing a ventilator sash, and the lower pulley or sprocket being operatively connected with a manually operable driving mechanism, and

to limit the longitudinal movement of the chain, I employ a flexible link connected between the reaches of said ventilator actuating chain.

These and other objects will be more apparent from the following detailed description when considered in connection with the accompanying drawings wherein:

Figure 1 is a side elevational view of a ventilator operating mechanism which is representative of one embodiment of my invention, said mechanism being shown in operative association with a greenhouse ventilator sash;

Figure 2 is an enlarged side elevational view of the lower portion of the mechanism disclosed in Figure 1, the flexible connecting link being secured at its opposite extremities to the reaches of the actuating chain; and

Figure 3 is a view similar to Figure 2 in which the flexible connecting link is disclosed as being secured at one extremity to a portion of the greenhouse frame.

Referring now in detail to the drawings wherein like numerals have been employed to designate similar parts throughout the various figures, it will be observed that one embodiment of my improved ventilator operating mechanism includes an endless actuating means, designated generally by the numeral 2, which is disposed between a pair of suitable rotary members or sprockets 4 and 6 positioned at upper and lower extremities respectively of a suitable greenhouse frame member 8. This endless actuating means includes a chain portion 10 which is guided by the sprocket 6 and another chain portion 12 which is guided by the sprocket 4. Strips 14 are interposed between extremities of the chain portions 10 and 12 and it will be clear that in order to move the endless actuating means it is only necessary to impart a rotary movement to the sprocket 6.

The sprocket 6 may be conveniently rotated through the agency of a hand wheel 16, which is operatively connected to the sprocket 6 by means of a suitable worm wheel mechanism, indicated generally by the numeral 18, which is supported by means of a suitable clamping sleeve 20 upon the frame 8.

To limit the distance through which the endless actuating means 2 may be moved in response to the manipulation of the hand wheel 16, I provide a flexible connecting means or link 22. In Figures 1 and 2 I have shown this flexible connecting link connected between the reaches of the chain 10. Obviously the limiting movement of the endless actuating means will be determined by the length of the connecting link. In Figure 3 I have shown the flexible connecting link 22 as being connected at one extremity to one of the reaches of the chain 10 and the opposite extremity connected or secured to the frame 8. This link 22 provides a very simple and effective means for limiting the movement or travel of the endless actuating means and its practical adaptability will be more apparent in Figure 1 wherein I have disclosed my improved operating mechanism in association with a greenhouse ventilator sash 24.

This greenhouse ventilator sash is provided with a rack bar 26 which is pivoted at its upper extremity to the underside of the sash 24 and which is maintained in operative association with a pinion 28 through the agency of a suitable guiding device 30. The pinion 28 is mounted upon a shaft 32 which also carries the sprocket 4 and it will be apparent that when rotation is imparted to the sprocket 4 in a clockwise direction, as viewed in Figure 1, the rack and pinion mechanism just described serves to elevate or open the sash 24. Likewise when a counter-clockwise rotation is experienced by the sprocket 4, said sash will be lowered into a closed position. The length of the flexible link 22 is such that when the sash has been raised to a proper predetermined position, as shown in Figure 1, said link will be rendered taut and hence will prevent the further elevation of the sash. Experience has shown that when the degree of movement of the endless flexible actuating means is not controlled, attendants within the greenhouse inadvertently cause the sash to be opened too far. By employing my convenient connecting link, I am able to control the actuation of the sash and hence preclude the unsatisfactory results which have heretofore been experienced.

From the foregoing it will be appreciated that my invention provides a very simple, economical and effectively operable means whereby the movement of ventilator sashes and other devices of like nature may be effectively controlled. Obviously my invention is not limited to the use of any particular type of endless actuating means, nor is it limited to any particular type of connecting link. In other words, the sprocket and chain mechanism and the particular type of flexible link connected therewith is illustrative of one embodiment of my invention. Other modifications and applications of my inven-

tion may be made without departing from the spirit and scope of the appended claims. The length of the flexible connecting link which I employ will obviously determine the extent of movement which may be experienced by the endless conveyor means and consequently the extent of upward displacement of the ventilator sash. In this manner I am able to obviate the inconvenience and injurious results which are experienced when the extent of movement of a sash actuating chain is not limited.

Having thus described my invention, what I claim as new and desire to secure by Letters Patent is:

1. In combination with an endless actuating means, a link member connected between the reaches of said endless actuating means to prevent the movement thereof beyond a predetermined limit.

2. A device for limiting the movement of an endless actuating member comprising a member adapted to be connected directly to said actuating member whereby movement of said actuating member is limited by said second named member.

3. A device for limiting the movement of an endless chain actuating member comprising a flexible member adapted to be connected between reaches of said chain to prevent movement of said chain beyond a predetermined limit.

In witness whereof, I have hereunto subscribed my name.

PHILIP L. MCKEE.
